UNITED STATES PATENT OFFICE

FERMINIO SPERANZA, OF AVONMORE, PENNSYLVANIA

WINDOW FLY STOP

Application filed October 7, 1925. Serial No. 61,080.

My present invention has reference to a simple and effective means for preventing flies, other insects or drafts entering between the sashes of a window casing.

5 A further object is to arrange upon the lower rail of the upper sash in a window casing a plate which will contact with the outer face of the pane on the lower sash, to arrange in the window casing a screen carrying frame 10 which is disposed outwardly with respect to the lower sash and to secure on the top of the said frame a second plate which has a wiping engagement with the outer face of the pane of the said lower sash, whereby insects and 15 drafts will be prevented from entering between the sashes when the lower sash is raised and likewise whereby the glass pane in the lower sash will be wiped by the plates when the said sash is raised or lowered.

20 The drawing which accompanies and forms part of this application illustrates the improvement.

In the drawings:

Figure 1 is a sectional view approximately 25 on the line 1—1 of Figure 2.

Figure 2 is a sectional view approximately on the line 2—2 of Figure 1.

Figure 3 is a fragmentary perspective view of one of the plates which may be employed.

30 In the drawings, the numeral 1 designates a window casing having slidably arranged therein an upper and a lower sash. The lower or meeting rail of the upper sash is indicated for distinction by the numeral 2 and 35 on the under face of this rail there is supported a plate 3, preferably of metal. The plate extends outwardly from the rail 2 and has a wiping engagement with the inner face of the pane of glass 4 in the lower sash 5.

40 Secured in the casing, outwardly of the lower sash there is a screen carrying frame 6. On the top rail of this frame 6 there is secured an inwardly directed plate 7. One of the plates has secured on its outer edge a roll of 45 fabric such as an ordinary rope 8. This fabric, of course, contacts with one of the faces of the glass pane of the lower sash. The rope or like fabric is comparatively thin and projects only a slight distance beyond the 50 open edge of the plate and the faces of said

plate. The roll being of fabric will yield when in contacting engagement with the pane so that all parts of the pane will be thus engaged by the rope.

Having described the invention, I claim:—

A fly stop, comprising a plate designed to be secured to the under face of an upper rail of a window sash and to terminate adjacent the glass pane in a lower sash and a roll of comparatively thin fabric secured to the outer edge of said plate, said roll adapted to frictionally engage the glass pane of a lower sash.

In testimony whereof I affix my signature.

FERMINIO SPERANZA.
